J. NEUBURGER

PULVERIZING MACHINE

Filed Feb. 21, 1925

Jacob Neuburger

Daniel F. Brennan.

Attorney.

UNITED STATES PATENT OFFICE.

JACOB NEUBURGER, OF CHICAGO, ILLINOIS.

PULVERIZING MACHINE.

Application filed February 21, 1925. Serial No. 10,744.

To all whom it may concern:

Be it known that I, JACOB NEUBURGER, a citizen of the United States, residing at Chicago, in the county of Cook and State 5 of Illinois, have invented a new and useful Improvement in Pulverizing Machines, of which the following is a specification.

The invention relates broadly to pneumatic pulverizing devices and provides a 10 device for pulverizing a wide variety of materials, such as lime stone, coffee, and any other material that can be broken up by impact and friction.

While I have referred to the present machine as a "pulverizing" device I attach no limitation to the term, as the principles of the invention can be embodied in a machine for breaking up particles of matter to different degrees of fineness of larger or 20 smaller size than what might be considered a pulverulent state. One of the objects of the invention is to provide a device which will be immune to stoppage or irregular action from clogging.

25 Another object is to provide a device that will be simple of construction, inexpensive to manufacture and easily operated at a small cost so as to be highly efficient.

A preferred embodiment of the invention 30 is illustrated in the accompanying drawing in which:

Fig. 1 is a side elevation partly broken away to show a portion in section.

Fig. 2 is a transverse section taken on 35 line 2—2 of Fig. 1, and

Fig. 3 is a fragmental section through the lower part of the device shown on an enlarged scale.

The operation of pulverizing the material 40 and of separating the pulverized particles from the unpulverized particles are both performed in a receiving tank comprising a cylindrical shell 6 and upper and lower frustro conical shells 7 and 8 respectfully. 45 The large circular ends of both of the conical shells are formed with vertically extending flanges 9 and 10. These form cylindrical surfaces to which are secured annular attaching rings 11 and 12 of angle 50 section, which in turn are riveted to companion attaching rings 13 and 14 at the top and bottom edges of the cylindrical shell 6.

The small circular ends of the conical 55 shells 7 and 8 are also formed with verti-

cally extending flanges 15 and 16 to which are secured flanges 17 and 18 respectively.

An extension pipe 19 has flanges 20 and 21 threaded to its ends. The upper flange 20 is secured to its companion flange 18 on 60 the conical shell 8 by means of bolts or the like and the lower flange 21 is secured to a bottom plate or cap 22 in which a central threaded opening 22' is provided.

Secured to this bottom plate or cap 22 65 in spaced relation to each other are bent bars 23 forming supporting legs.

To the top flange 17 of the conical shell 7 a flanged elbow 24 having a boss 24' integral therewith is secured. To the other 70 flange of the elbow a discharge pipe line 25 connects. A chute 26 is connected to an inlet 27 entering the lower conical shell 8 and has its upper end flanged as at 28 to connect with a flanged hopper 29 into which 75 the previously ground or broken up material is placed.

On opposite sides of the center line of the cylindrical shell 6 disposed and in the same horizontal plane, are suspension rods 80 30 extending therethrough and held firmly in place by means of nuts on the ends of said rods drawn tightly against bosses formed integral with the side walls of the shell.

A baffle plate 31 of a diameter less than the diameter of the shell 6 is hung from the rods 30 by U-bolts 32, the baffle plate being disposed concentrically of said shell to leave an annular opening for the passage 90 of a stream of air for carrying away the pulverized material.

A pneumatic discharge nozzle 33 is supported in the lower part of the device in 95 position to discharge against the bottom of said baffle plate at its center. This nozzle comprises a drum 34 having large openings 34' adjacent its lower end preferably in the same horizontal plane. Within said drum and above said openings is positioned a conical wall or partition 35 which is preferably integral with the drum. This conical wall or partition has a threaded boss at its apex into which screws a nipple 36. A closure cap 37 has threaded engagement with said drum and nipple. A blast discharge pipe 38 having its discharge end reduced in size is coupled to the end of the nipple 36. The bottom end of the drum 34 has threaded engagement with the central threaded open- 100 105 110

ing 22' in the bottom plate 22, and a plug 40 having a central threaded opening in which an air supply pipe 41 is secured, closes the bottom of the drum through its 5 threaded engagement in the opening 22' in the bottom plate 22.

Material that has previously been ground or broken up in small particles is put into the hopper from which a continuous 10 discharge will occur over and around the drum 34 of the nozzle. The air blast coming in through the air jet 41' at the upper end of the air supply pipe 41 will cause the particles of material to be drawn through the 15 apertures 34' at each side and into the air stream, similar to an injector action, forced upwardly through the blast nozzle to forcibly strike against the baffle plate 31. The 20 force of the impact of these particles under the velocity of this high velocity air blast will quickly pulverize them. After striking the baffle plate or impact surface 31 the particles of material that have not been 25 pulverized will again drop into the extension pipe or pocket 19 whereby they will be in a position to again pass into the apertures 34' of the drum and up through the air blast nozzle again. The friction of their passage 30 through the blast nozzle and their friction against each other will aid in the pulverizing 35 action. An auxiliary air line 43 entering the elbow 24 discharges air in the direction of the outlet 25, thus tending to aid the propulsion of the discharging dust or pulverized material.

It will be observed that from the point where the particles are first introduced into the air stream around the tip of the air jet 41' to the point where they strike the impact plate 31 they travel in a substantially straight path. The absence of bends or sharp angle deflections in the path of the particles while they are under the impelling influence of the air stream allows the particles 45 to retain the velocity of the air stream from start to finish of their impelled motion and thus avoids all tendency of the device to clog. The lateral introduction of the particles through the relatively large openings 41' to the sides of the upwardly directed air jet automatically proportions the rate at which the particles enter the air stream, and this also avoids tendency to clog.

The air stream on striking the impact surface 31 is deflected outwardly across the bottom of this surface to the annular opening 44 between the impact surface and the side walls of the shell 6. Because of the relatively large area of this annular passageway 50 with respect to the nozzle 33 coupled with initial retardation of the air stream by contact with the baffle plate 31, the flow of air passing up through this passageway drops in velocity. The area of the passageway 41 55 is not, however, so large as to produce such

a reduction in the rate of flow of air therethrough as will be insufficient to entrain the pulverized particles. The resultant velocity of this upwardly passing sheath of air is proportioned by the size of the passageway 70 44 so that it will be of sufficient velocity to sustain the pulverized particles against the force of gravity but will be of insufficient velocity to carry the unpulverized particles upwardly through this opening, whereupon 75 these unpulverized particles will drop back into the pocket 19. The horizontal lateral deflection of the air stream forms a curtain of air which is very efficacious for picking up and carrying away the pulverized particles. Obviously, any other gas than air may be employed if any particular action, chemical or otherwise, is desired, and this gas or air may be heated or chilled if desired.

While the preferred form of the invention 80 has been illustrated it is not intended that the same be limited to the exact details and structure shown but as the invention is capable of numerous modifications and changes.

I claim:

1. The method of pulverizing and conveying materials which includes entraining and projecting particles of such materials by a high velocity non-tortuous stream of fluid against the center of a surface substantially 95 transverse to the direction of flow to break up the particles by impact upon said surface, producing a moving curtain of air at and substantially parallel to said surface for causing the particles thus formed to pass 100 across the surface of the edges thereof, and simultaneously producing an accelerated stream of fluid past the edges of said surface and transversely thereof for positively extracting the smaller particles from the 105 first mentioned stream.

2. In a device of the character described, in combination, a chamber for the reception of bulk materials, a perforate drum disposed vertically in said chamber and having 110 an axial outlet, a receiving and separating chamber above said drum, a baffle plate disposed in said receiving chamber transversely to the axial outlet of said drum and peripherally spaced from the walls of said receiving chamber to afford a continuous passageway of constricted area, and a nozzle axially disposed in said drum for delivering a stream of fluid under high velocity through said drum to entrain materials deposited 115 therein and deliver them with impact against said baffle plate.

3. In a device of the character described, in combination, a chamber for the reception of bulk materials, a perforated drum disposed vertically in said chamber and having an axial outlet, a receiving and separating chamber above said drum, a baffle plate disposed in said receiving chamber transversely to the axial outlet of said drum and 125 130

peripherally spaced from the walls of said receiving chamber to afford a continuous passageway of constricted area, and a nozzle axially disposed in said drum for delivering 5 a stream of fluid under high velocity through said drum to entrain materials deposited therein and deliver them with impact against said baffle plate, and means for introducing materials directly into said first 10 mentioned chamber remote from said baffle plate.

4. In a device of the character described, in combination, a chamber for the reception of bulk materials, a perforated drum disposed vertically in said chamber and having an axial outlet, a receiving and separating chamber above said drum, said receiving chamber having an outlet, a baffle plate disposed in said receiving chamber transversely 15 to the axial outlet of said drum and peripherally spaced from the walls of said receiving chamber to afford a continuous passageway of constricted area, a nozzle axially disposed in said drum for delivering a 20 stream of fluid under high velocity through said drum to entrain materials deposited therein and deliver them with impact against said baffle plate, and means for creating an auxiliary stream of fluid in the 25 30 outlet of said receiving chamber.

5. In a device of the character described, in combination, a chamber for the reception

of material to be pulverized, a drum vertically disposed in said chamber and having transverse inlets placing said drum in direct lateral communication with said chamber, an axial outlet for said drum, a nozzle in said drum concentric with said outlet, a receiving chamber above said first mentioned chamber, a baffle plate disposed in said receiving chamber transversely to the vertical axis of said drum, and said nozzle discharging a stream of fluid through said drum which entrains such materials and impinges them against said baffle plate, the 40 material passing through a substantially rectilinear path from its induction into said stream to its point of impact upon said baffle plate.

6. In a device of the character described, in combination, a chamber for reception of material in bulk, a drum disposed within said chamber and provided with transverse inlets in direct lateral communication with said chamber, a constricted outlet for said drum provided with a tapering entrance, and an induction nozzle projecting into said drum substantially axially of said constricted outlet and spaced from but adjacent to the tapering entrance thereof. 50 55 60

In testimony whereof, I affix my signature at 10 South La Salle Street, Chicago, Illinois.

JACOB NEUBURGER.
